(57) **CLAIM**

The ornamental design for the grip for stylus or other writing or drawing instrument as shown and described.

DESCRIPTION

FIG. 1 is a top perspective view of a grip for a stylus or other writing or drawing instrument, wherein an exemplary stylus or other writing or drawing instrument is shown in broken lines and forms no part of the claimed design.

FIG. 2 is a bottom perspective view of the grip of FIG. 1. FIG. 3 is a top perspective view of a grip for a stylus or other writing or drawing instrument.

FIG. 4 is a bottom perspective view of the grip of FIG. 3.

FIG. 5 is a top plan view of the grip of FIG. 3.

FIG. 6 is a bottom plan view of the grip of FIG. 3.

FIG. 7 is a side elevation view of the grip of FIG. 3.

FIG. 8 is another side elevation view of the grip of FIG. 3.

FIG. 9 is an end view of the grip of FIG. 3; and,

FIG. 10 is another end view of the grip of FIG. 3.

1 Claim, 4 Drawing Sheets
